CLASP

Benjamin Ogush, New York, N. Y., assignor to
 Katz & Ogush, Inc., New York, N. Y., a corporation of New York

Application June 30, 1934, Serial No. 733,185

8 Claims. (Cl. 24—201)

This invention relates to an improvement in a clasp or fastening device for wrist watches, bracelets, necklaces, or any other articles of jewelry to which it may be applied. The device produced according to my invention is one of simple and sturdy construction, having but few parts and being thus extremely unlikely to get out of order, at the same time affording a firm and secure connection for the two ends of the encircling band.

10 A further object of the invention is to provide an extremely safe connection for the opposite ends of a wrist band or the like, with which the possibility of the wrist band, bracelet, or other article of jewelry becoming lost is extremely unlikely.

More specifically, the device consists of a pair of clasp members hinged together and adapted to removably hold one of the ends of the wrist band. The two clasp members frictionally engage one another to hold them in closed relationship, and a very efficient and simple safety clasp is provided for preventing the inadvertent pivotal separation of the two clasp members.

In the accompanying drawing, wherein an embodiment of the invention is shown, Fig. 1 is a plan view of the improved clasp as applied to a wrist band or cord; Fig. 2 is a side elevation of the improved clasp showing the same in open condition; Fig. 3 is a sectional view on the line 3—3 of Fig. 2, looking in the direction of the arrows; Fig. 4 is a longitudinal sectional view through the structure of Fig. 1; and Fig. 5 is a perspective view of the upper end of the closure member showing the hinged locking member.

35 At 1 is shown one of the ends or loops which is attached to wrist cords 4 in the conventional way. For this purpose, the member 1 is formed with a pair of parallel sleeves 3 into which the ends of the cords fit and are gripped or held by any of the conventional gripping means used in the jewelry industry for this purpose. In the event that a flat wrist band or strap is used, the shape of the parts 3 of the member 1 will be altered accordingly as is well understood in this art. The other end 45 of the wrist encircling cords 4 are received and held in the sleeve portions 3 of a loop member 2.

The body portion 25 of the clasp consists of a trough-shaped member provided with spaced parallel side walls 7, an end wall 8, and a bottom 10. The member 1 is formed with a cross-bar 6 which is rigidly secured between the side walls 7 of the body portion 25, so that the body portion is thus fixedly secured to the member 1. The bottom 10 of the body portion 25 is in the form of a flat plate spring which, near its free end, presses against

the hub 11 of a closure member 13. Said closure member has its hub 11 pivoted on the pivot pin 12 between the side walls 7 of the body portion 25. The side walls 7 are formed with recesses 9 for the reception of the cross-bar 5 on the member 2.

50 In Figs. 1 and 4, the clasp is shown in closed position where it will be seen that the closure member 13 has been folded down to overlie the top or open upper end of the body portion 25. When the closure member is in this closed position, its laterally formed end 16 frictionally engages the end wall 8 of the body portion 25 so that the two main clasp elements, comprising the closure member 13 and the body portion 25, are held together with a so-called "snap" connection.

55 The pressure of the spring 10 against the hub 11 of the closure member aids in holding the two clasp members in their closed relationship and prevents inadvertent pivotal movement of one of the parts with respect to the other. When the 75 two clasp members are in their closed position, as shown in Fig. 4, it will be seen that the cross-bar 5 on member 2 is located in the recesses 9 formed in the side walls 7 of the body portion 25, so that the member 2 has this integral portion 80 of its body held between the two clasp members.

70 At its free end, the closure member 13 is formed with an elongated slot 14 which also extends into the hook part 16, as clearly shown in Fig. 5. Pivotedly mounted in said slot at the end of the 85 closure member 13 is a locking member 18 which is supported on the pivot pin 17. Said locking member is formed with a hook-shaped part 19 which is adapted to project through the slot 14 when the clasp is in closed position, and enters 90 into interlocking engagement with the fixed cross-bar 6 on the member 1, as shown in Fig. 3.

From the foregoing, the operation of the clasp will be clearly understood. The clasp is in its open position as shown in Fig. 2. To close the 95 clasp, the member 2 is first placed in position, so that its cross-bar 5 lies in the recesses 9, as shown in Fig. 4. The closure member 13, as well as the locking member 18 carried thereby are swung down together toward the body portion 25 of the clasp, by the pressure of a finger, as shown in dotted lines in Fig. 2 until the lateral end portion 16 of the closure member 13 enters into frictional engagement with the end wall 8 of the body portion. At the same time, the 105 pressure of the finger on the locking member 18 causes the hook portion 19 thereon to be forced through the slot 14 to snap into interlocking engagement with the cross-bar 6 on the member 1. The surface 21 on the hook portion 19 110

also frictionally engages the end 15 of the slot 14, so that the locking member is very securely held in its closed position.

To open the clasp, it is merely necessary to engage the portion 20 on the locking member 18 with the finger nail and raise said member 18, thereafter raising the closure member 13 so that the loop member 2 can be lifted out of the recesses 9 and drawn away from the clasp.

10 The connection between the various movable parts of the clasp is extremely secure because of the numerous points of frictional engagement of the parts with one another. For example, the spring 10 resists free swinging movement of the closure member 13 with respect to the body portion 25. The frictional engagement of the projecting lateral end 16 on the closure member 13 with the end wall 8 of the body portion also acts to prevent inadvertent separation of the part 13 and the body portion 25. The engagement of the hook part 19 with the cross-bar 6 holds the two parts 13 and the body portion 25 also securely together. At the same time the frictional engagement of the part 21 of the hook 15 19 with the end 15 of the slot 14 prevents the hook from being easily raised and separated from its interlocked engagement with the cross-bar 6.

It will be apparent that a great degree of security is attained by the use of the clasp shown, and the possibility of the loss of valuable jewelry 30 will be prevented.

What I claim is:

1. A clasp comprising, a body portion adapted for securement to one end of a wrist-encircling element, means on said body portion for the reception of a loop member attached to the other end of the wrist-encircling element, a closure member hinged to the body portion and adapted to be folded down to overlie the body portion, a locking member hinged at one end of the closure member, the closure member being apertured, said locking member being provided with means movable through the aperture in the closure member for engagement with a part of the body portion when said locking member is folded down against the closure member.

2. A clasp comprising, a body portion having side walls, said side walls having recesses for the reception of a cross bar formed on an element attached to one end of a wrist-encircling member, a closure member hinged at one of its ends between the side walls of the body portion and adapted to be folded down to overlie the top of the body portion and to overlie the cross bar and retain it in the recesses, a locking member hinged at the free end of the closure member and adapted to be folded down to overlie the closure member when said member has been folded down against the body portion, the closure member being provided with a slot, and a hook-shaped element on the locking member for entry through said slot to interlock with an element on the body portion when the locking member is folded down on top of the folded-down closure member.

3. A clasp having a body portion formed with a fixed cross bar, a closure member hinged at one end of the body portion and adapted to be folded down to overlie the body portion, means at the end of the closure member for frictionally engaging with the end of the body portion, the closure member being provided with a slot, a locking

member pivoted in said slot, and means on said locking member for interlocking with the cross bar on the body portion when said locking member is folded down on the closure member.

4. A clasp comprising, a pair of pivotally connected clasp members adapted to be brought together to removably hold a wrist-band end between them, a pivoted locking member secured on one of said clasp members, an aperture in the clasp member on which the locking member is secured, and means on the locking member for entry through said slot to interlock with a fixed element on the other clasp member to hold both clasp members together in interlocked relationship.

5. A clasp comprising, a pair of clasp members pivotally connected at one of their ends, a locking member pivoted to the first of said members at its end remote from the point of pivotal connection of the two clasp members, and means on said locking member for engaging and interlocking with a fixed element on the second of said clasp members when the two members are brought together.

6. A clasp comprising, a trough-shaped body portion provided with side walls, said walls being provided with recesses for the reception of the cross bar of a loop member attached to one end of a wrist-band or the like, a closure member hinged between the side walls at one end of the body portion and adapted to be folded down to overlie the top of the body portion and also to overlie the cross bar on the loop member when said cross bar is seated in the recesses, a locking member pivoted at one of its ends to the free end of the closure member at a point remote from the point of connection of the closure member with the body portion, said locking member having a projecting hook part, the closure member having an aperture through which the hook part projects when the locking member is folded against the closure member, and a fixed element extending between the side walls of the body portion and adapted for interlocking engagement with the hook part when said hook part is projected through the aperture.

7. A clasp comprising, a pair of clasp members pivotally connected together at one of their ends, the first of said clasp members being provided with an end adapted to snap into engagement with the end of the second clasp member to hold said members together in contiguous relationship, a locking member pivotally mounted at the end of the first clasp member, said first clasp member being slotted, and a projecting element on said locking member adapted to pass through said slot and frictionally engage one of the walls thereof, said element also interlocking with a fixed element on the second clasp member.

8. A clasp comprising, a body portion, an apertured closure member hinged thereto, a spring operative on the hinge of said closure member to resist pivotal movement of the closure member, a laterally extending free end on the closure member for frictional engagement with a part of the body portion, a locking member pivoted at the free end of the closure member, means on the locking member for entry through the aperture in the closure member to interlock with a fixed part of the body portion, said means frictionally engaging one of the walls of the aperture while in its position of interlock.

BEN. OGUSH.
